(57) CLAIM

The ornamental design for a pair of foot supporters, as shown and described.

DESCRIPTION

FIG. 1 is a front perspective view of a foot supporter illustrating my new design in a position of use;

FIG. 2 is a front perspective view thereof (the round pad presses the acupressure point named "Yusen" on the sole of a wearer's foot;

FIG. 3 is a front view thereof;

FIG. 4 is a rear view thereof;

FIG. 5 is a top view thereof;

FIG. 6 is a bottom view thereof;

FIG. 7 is left side view thereof; and,

FIG. 8 is a right side view thereof.

While a right foot version of the claimed design has been shown in the drawings, a left foot version is simply a mirror image thereof, and thus also encompassed by the claim herein.

The broken line showing of a wearer's foot in FIG. 1 is for the purpose of illustrating environment and forms no part of the claim.
